US0D1005433S

(12) **United States Design Patent** (10) **Patent No.:** **US D1,005,433 S**
(45) **Date of Patent:** **** Nov. 21, 2023**

(54) **FREESTANDING SLIDE**

(71) Applicant: **Shanghai Shiyao Technology Co., Ltd.**, Shanghai (CN)

(72) Inventor: **Feng Wang**, Shanghai (CN)

(**) Term: **15 Years**

(21) Appl. No.: **29/877,794**

(22) Filed: **Jun. 12, 2023**

(51) **LOC (14) Cl.** **21-03**

(52) **U.S. Cl.**

USPC **D21/818**

(58) **Field of Classification Search**

USPC D21/811, 814, 818-822, 826-827

CPC A63G 21/00-22; A63B 9/00; A63B

2009/006
